DOOR MECHANISM FOR BOXCARS

John H. Hopkins, Rawlins, Wyo.

Application June 7, 1944, Serial No. 539,137

1 Claim. (Cl. 20—30)

1

This invention relates to a novel door mechanism particularly applicable to grain-carrying box cars.

A prime object is to provide a novel construction capable of manufacture entirely or primarily of metal, and a construction wherein the door and all of the moving and locking parts are a unit.

In addition, it is aimed to provide a structure wherein the door is capable of being removed, swinging outwardly in opening, and wherein locking elements are provided which are operable by a vertically movable plate having V or cam connections with the locking means.

The more specific objects and advantages will become apparent from a consideration of the description following taken in connection with accompanying drawings illustrating an operative embodiment.

In said drawings:

Figure 1 is a fragmentary elevation of a grain-carrying box car equipped with door mechanism according to the invention;

Figure 2 is a fragmentary elevation of the parts of Figure 1 but with the door mechanism locked;

Figure 3 is a vertical section taken on the line 3—3 of Figure 2;

Figure 4 is a vertical section taken on the line 4—4 of Figure 2;

Figure 5 is a horizontal sectional view taken through the parts of Figure 1; and

Figure 6 is a horizontal sectional view taken on the line 6—6 of Figure 2.

Referring specifically to the drawings wherein like reference characters designate like or similar parts, 10 designates a side wall of a conventional box car or the like, of the type primarily adapted to carry grain. This wall has a door opening 11 therein, surrounded by a door frame 12 including uprights 13 at the sides thereof.

Said doorway or opening 11 is adapted to be closed by a door structure generally designated 14. This door structure has an inner panel 15 of approximately the same area as the door opening and on the outside has auxiliary or outer panels 16, which are spaced from the panel 15 by studs 17, and the panels 15 and 16 are secured in place to such studs.

Slidably mounted for longitudinal movement in slots 18 of the studs 17, are locking bolts or bars 19 adapted for engagement with and disengagement from keeper recesses 20 in the uprights 13.

An actuating plate 21 for the locking bolts 19 is slidably mounted against the panel 15 between the innermost studs 17. In either face of the actuating plate 21, V or cam grooves 22 are provided, and inwardly-extending projections 23 extend inwardly from the bolts 19 into the grooves 22. Such projections preferably include rollers 24 to enable operation with minimum friction.

2

At each upper corner, the door has pintles or trunnions 25 securely fastened thereto and such trunnions project beyond the door and are journaled in sockets or openings 26 in the uprights 13. Such sockets or openings 26 are preferably open at the front as at 27 to enable the door to be bodily removed and replaced when desired.

It is clear that the construction may be made of any suitable materials, and that all movable parts are carried by the door. The door may be made entirely of metal or partly of metal, as preferred. In some instances, the panels 15 and 16 will be made of metal and the remaining part made of wood.

In Figure 2, it will be realized that the door is shown in locked position since the locking elements 19 are extended into the keeper openings 20. However, in order to unlock the door so that the same may be swung on the pintles 27 to the dotted-line position of Figure 3, outwardly of the car, the plate 21 is moved upwardly to the position of Figure 1. Through said movement of the plate 21, the cam grooves 22 through coaction with the rollers 24 retract bolts 19 so that they free the keeper openings 20 as shown in Figures 1 and 5.

Various changes may be resorted to provided they fall within the spirit and scope of the invention.

I claim as my invention:

A door structure of the character described comprising a door section provided with a back wall and a pair of horizontally spaced front walls, said front walls being provided with vertical walls at their vertical edges secured to the back wall and each formed with an opening therein, a vertically slideable plate on the front side of the back wall formed with a V-shaped groove in its front surface, a bolt disposed through the openings of the vertical walls of each front wall and provided with a rearward projection disposed into the adjacent leg of the V-shaped groove, said bolts being adapted to move horizontally away from each other upon downward movement of the vertically slideable plate.

JOHN H. HOPKINS.
